CLAIM

The ornamental design for a grocery bag stand, as shown and described.

DESCRIPTION

FIG. 1 is a front left upper perspective view of a grocery bag stand showing our new design;
FIG. 2 is a front elevation view thereof, the rear elevation view thereof being a mirror image thereof;
FIG. 3 is a left side elevation view thereof, the right side elevation view thereof being a mirror image thereof;
FIG. 4 is a top plan view thereof; and,
FIG. 5 is a bottom plan view thereof.
